UNITED STATES PATENT OFFICE.

VICTOR L. RONCI, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed December 19, 1924. Serial No. 756,863.

This invention relates to electron discharge devices and more especially to such devices capable of handling large amounts of power.

5 In certain types of such devices, the electrode enclosing vessel comprises a cylindrical metal anode portion having flared ends and a glass portion fused to each flared end. The cathode is supported from one glass 10 portion and the control electrode is supported from the opposite glass portion.

It is the object of this invention to provide a unitary structure of the above type in which the water jacket is consolidated with 15 the cylindrical anode of the device.

In the structure of this invention a member is secured to each end of the anode and a body surrounding the anode and composed of a number of sections joined together is 20 secured to said end members. Preferably, said body is formed in two parts, portions of said parts being bent to form projections, and the corresponding projections of the two parts or halves are fused together. 25 This arrangement provides a water-tight enclosure which can be easily assembled and provides a supporting extension whereby the complete structure may be supported from a panel or other mounting surface. The im- 30 proved water jacket is provided with inlet and outlet ports to which are attached removable hose couplings having a spring clamp and lever pivoted to the body of the coupling. The spring clamp engages a 35 shoulder on the inlet and outlet ports of the water jacket. This arrangement affords a simple and efficient water-tight coupling which may be readily disconnected from the water-jacket.

40 Referring to the drawing:

Fig. 1 shows an electron discharge device, partly in section, embodying this invention.

Fig. 2 is a cross sectional view of Fig. 1 45 on the line 2-2 and illustrates the removable hose coupling.

The electron discharge device comprises a cylindrical metal anode portion 10 having the ends flared outwardly and reduced to a 50 tapered edge. Glass portions 11 and 12 are fused to the tapered ends in accordance with the disclosure in W. G. Houskeeper Patent 1,294,466, issued February 18, 1919 and entitled Combined metal and glass structure 55 and method of making same. An inwardly

projecting stem 13 is fused to the end of the glass portion 11 and carries a filament supporting structure comprising a collar 14, supporting rods 15 and 16 and a base 17. A cathode 18 is supported between the base 60 17 and insulating block 19. The ends of the filament are connected to leading-in wires 20 and 21 which are sealed in tubular extensions 22 and 23 in the stem 13, in accordance with W. G. Houskeeper Patent 65 1,293,441, dated February 4, 1919 and entitled Combined metal and glass structures and method of forming the same.

A similar glass stem 24 is fused to the end of glass portion 12 and projects within the 70 vessel. This stem carries a collar 25 to which are attached rods 26 and 27, which support the helical wire control or grid electrode 28. A leading-in wire 29 is connected to the collar 25 and sealed through the glass 75 portion 12.

The wall of the metallic anode 10 is reduced in thickness on the exterior surface at each end thereof to form circular seats 31 80 and 32. Prior to the flaring of the ends of the anode 10, a perforated disc 33 the diameter of which is substantially the same as the outer diameter of one end of the anode 10, is forced down on the thin wall 85 end of the anode until it is seated on the ridge 31. This disc is securely attached to the anode by soldering or otherwise sealing the juncture of the anode 10 and the disc 33. A similar disc 35 is arranged on the other 90 end of the anode 10 and sealed to the anode at 36. The thin walled ends of the anode are then flared in any suitable manner and reduced to a knife edge. Each disc is provided with a peripheral groove 37 on the 95 inner surface thereof. These grooves are arranged to receive semi-cylindrical metal walls 38 and 39. Each of these walls is provided with angular extensions 40 and 41 arranged on the longitudinal ends thereof. A 100 pair of apertures 42 are drilled in the angular ends for mounting purposes.

The cooperation of the semi-circular edges of the walls 38 and 39 and the grooves 37 in the discs provides a snug fit when these members are joined together. The contacting edges of the walls of the discs are soldered or otherwise sealed to prevent any leaks. The face-to-face relation of the extensions 40 105 and 41 of each wall, provides considerable 110

surface for welding the semi-circular walls together, whereby the space between the anode 10 and the walls of the jacket will be water-tight.

- 5 The wall 38 is provided with a tubular port 43 having a shoulder 44, projecting from the wall 38, adjacent the projection 40 and is fused or soldered to the wall near one end thereof. A similar tubular port 45, 10 is fused to the wall 39 and projects from the wall at the opposite end from the port 43. A tubular coupling member 46 is provided with a projecting collar 47 on one end which fits into the recess 48, of the tubular port. 15 A reduced portion 49 on the other end of the coupling, receives a flexible hose connection 50. A U-shaped lever member 51 bent to follow the contour of the coupling is pivoted at 52 adjacent the projection 47. A resilient 20 wire clamp 53 is attached to the lever 51 and swings easily in its own arc. This clamp comprises a semi-circular portion which is adapted to fit over the shoulder 44 of the port, and a loop portion on each side and at 25 right angles to the semi-circular portion. A soft rubber washer 54 is arranged between the opposed faces of the coupling and the

port and provides a water-tight connection when these members are clamped together. 30

Although the invention has been disclosed with reference to a particular construction, it is apparent that various detailed modifications may be made without departing from the scope of the invention as recited in the 35 appended claim.

What is claimed is:

In combination, an electron discharge device having an external anode with flared ends, glass portions fused to said flared ends, 40 an electrode supported from each of said glass portions, of a water jacket surrounding said anode, said jacket comprising a pair of perforated discs welded to said anode, one near each end thereof and a body portion 45 consisting of two semi-cylindrical sections, portions thereof being bent to form a pair of projections on each part, corresponding projections of the two parts being welded together and the two parts being welded at 50 their ends to said pair of discs.

In witness whereof, I hereunto subscribe my name this 17th day of December A. D., 1924.

VICTOR L. RONCI.
